CLAIM

I claim the ornamental design for a bottle, as shown and described.

DESCRIPTION

FIG. 1 is a front Elevation view of a bottle showing the present invention, the left side, right side and rear elevation view being identical;

FIG. 2 is a top plan view thereof; and,

FIG. 3 is a bottom plan view thereof.

The portions illustrated in phantom forming no part of the design.

1 Claim, 3 Drawing Sheets**FIG. 1**

FIG. 2

FIG. 3
